(57) **ABSTRACT**

A gaming apparatus according to the present invention comprises: a roulette wheel including a plurality of pockets associated with respective numbers in advance; a memory for storing a plurality of control data for controlling the gaming apparatus so as to provide a relatively high weight on a probability that a ball is housed in any of the pockets constituting a single group, the single group belonging to a plurality of groups each of which consists of a first predetermined-number of the plurality of pockets, and the plurality of control data associated with each of the groups; a plurality of stations for players to play games; and a controller, the controller programmed to execute the following processings of:

(a) controlling rotation of the roulette wheel and launching of the ball by referring to a single control data out of the plurality of control data, and

(b) selecting another control data different from the single control data, out of the plurality of control data, to set the selected control data as a reference target, when a bet is placed on any of the pockets belonging to a group having the relatively high ball-housing probability at a second predetermined number or more of the stations among the plurality of stations.

GAMING APPARATUS AND PLAYING
METHOD THEREOFCROSS-REFERENCE TO RELATED
APPLICATIONS

This application claims benefit of priority based on U.S. Provisional Patent Application No. 60/858,931 filed on Nov. 15, 2006. The contents of this application are incorporated herein by reference in their entirety.

BACKGROUND OF THE INVENTION

1. Field of the Invention

The present invention relates to a gaming apparatus such as a roulette gaming machine, bingo gaming machine and the like, and a playing method of the same.

2. Discussion of the Background

Conventionally, when roulette games are played, a dealer throws a ball onto a roulette wheel, in general. However, in recent years, automatization of such roulette games has been advanced, and there have been suggested gaming apparatuses capable of processing roulette games in a full automatic manner, without the dealer throwing in the ball.

Among such gaming apparatuses, there are gaming apparatuses capable of throwing in a ball using air, as disclosed in WO 04/094013 A1. Gaming apparatuses which process roulette games in a full automatic manner are desired to drop and house a ball into respective pockets with an even probability. Therefore, among these gaming apparatuses, there are some gaming apparatuses designed to include a ball track having concavities and convexities on its surface for disturbing the behavior of the ball, in order to cause the ball to drop into respective pockets with an even probability.

It is an object of the present invention to enable changing the probabilities that a ball is housed in respective pockets as required, thereby offering new entertainment.

The contents of WO 04/094013 A1 are incorporated herein by reference in their entirety.

SUMMARY OF THE INVENTION

According to a first aspect of the present invention, there is provided a gaming apparatus having the following structure.

That is, the gaming apparatus according to the first aspect of the present invention is a gaming apparatus comprising: a roulette wheel including a plurality of pockets associated with respective numbers in advance; a memory for storing a plurality of control data for controlling the gaming apparatus so as to provide a relatively high weight on a probability that a ball is housed in any of the pockets constituting a single group, the single group belonging to a plurality of groups each of which consists of a first predetermined number of the plurality of pockets, and the plurality of control data associated with each of the groups; a plurality of stations for players to play games; and a controller. The controller programmed to execute the following processes of: (a) controlling rotation of the roulette wheel and launching of the ball by referring to a single control data out of the plurality of control data, and (b) selecting another control data different from the single control data, out of the plurality of control data, to set the selected control data as a reference target, when a bet is placed on any of the pockets belonging to a group having the relatively high ball-housing probability at a second predetermined number or more of the stations among the plurality of stations.

2

According to a second aspect of the present invention, there is provided a gaming apparatus having the following structure.

That is, the gaming apparatus according to the second aspect of the present invention is a gaming apparatus comprising: a roulette wheel including a plurality of pockets associated with respective numbers in advance; a memory for storing a plurality of control data for controlling the gaming apparatus so as to provide a relatively high weight on a probability that a ball is housed in any of the pockets constituting a single group, the single group belonging to a plurality of groups each of which consists of a first predetermined number of the plurality of pockets, and the plurality of control data associated with each of the groups; a plurality of stations for players to play games; and a controller. The controller programmed to execute the following processings of: (a) controlling rotation of the roulette wheel and launching of the ball by referring to a single control data out of the plurality of control data, (b) counting the number of games played, (c) counting the number of high-probability bets indicating the number of games in which a bet is placed on any of the pockets belonging to a group having the relatively high ball-housing probability at a second predetermined number or more of the stations among the plurality of stations, (d) calculating frequency of high-probability bets, that is frequency of games in which a bet is placed on any of the pockets belonging to a group having the relatively high ball-housing probability at the second predetermined number or more of the stations, based on the number of games and the number of high-probability bets, and (e) selecting another control data different from the single control data, out of the plurality of control data, to set the selected control data as a reference target, when the frequency of high-probability bets exceeds a predetermined frequency.

According to a third aspect of the present invention, there is provided a gaming apparatus having the following structure.

That is, the gaming apparatus according to the third aspect of the present invention is a gaming apparatus comprising: a roulette wheel including a plurality of pockets associated with respective numbers in advance; a memory for storing a plurality of control data for controlling the gaming apparatus so as to provide a relatively high weight on a probability that a ball is housed in any of the pockets constituting a single group, the single group belonging to a plurality of groups each of which consists of a first predetermined number of the plurality of pockets, and the plurality of control data associated with each of the groups; a plurality of stations for players to play games; and a controller. The controller programmed to execute the following processings of: (a) controlling rotation of the roulette wheel and launching of the ball by referring to a single control data out of the plurality of control data, (b) determining a number corresponding to one of the pockets with the ball housed therein as a winning number, and (c) selecting another control data different from the single control data, out of the plurality of control data, to set the selected control data as a reference target, when a bet is placed on any of the pockets belonging to a group having the relatively high ball-housing probability at a second predetermined number or more of the stations among the plurality of stations, and a prize is determined to be offered based on this bet and the determined winning number.

According to a fourth aspect of the present invention, there is provided a gaming apparatus having the following structure.

That is, the gaming apparatus according to the fourth aspect of the present invention is a gaming apparatus comprising: a roulette wheel including a plurality of pockets

associated with respective numbers in advance; a memory for storing a plurality of control data for controlling the gaming apparatus so as to provide a relatively high weight on a probability that a ball is housed in any of the pockets constituting a single group, the single group belonging to a plurality of groups each of which consists of a first predetermined number of the plurality of pockets, and the plurality of control data associated with each of the groups; a plurality of stations for players to play games; and a controller. The controller programmed to execute the following processings of: (a) controlling rotation of the roulette wheel and launching of the ball by referring to a single control data out of the plurality of control data, (b) determining a number corresponding to one of the pockets with the ball housed therein as a winning number, (c) counting the number of games played, (d) counting the number of prize offering, that is the number of games in which a bet is placed on any of the pockets belonging to a group having the relatively high ball-housing probability at a second predetermined number or more of the stations among the plurality of stations, and a prize is offered based on this bet and the determined winning number, (e) calculating frequency of prize offering, that is frequency of games in which a bet is placed on any of the pockets belonging to a group having the relatively high ball-housing probability at the second predetermined number or more of the stations among the plurality of stations, and a prize is offered based on this bet and the determined winning number, (f) selecting another control data different from the single control data, out of the plurality of control data, to set the selected control data as a reference target, when the frequency of prize offering exceeds a predetermined frequency.

According to a fifth aspect of the present invention, there is provided a playing method of a gaming apparatus having the following structure.

That is, the playing method of a gaming apparatus according to the fifth aspect of the present invention is a playing method of a gaming apparatus comprising the steps of: (a) controlling rotation of a roulette wheel and launching of a ball by referring to a single control data, the single control data selected out of a plurality of control data for controlling the gaming apparatus so as to provide a relatively high weight on a probability that the ball is housed in any of the pockets constituting a single group, the single group belonging to a plurality of groups each of which consists of a first predetermined number of pockets out of a plurality of pockets being included in the roulette wheel and being associated with respective numbers in advance; and (b) selecting another control data different from the single control data, out of the plurality of control data, to set the selected control data as a reference target, when a bet is placed on any of the pockets belonging to a group having the relatively high ball-housing probability at a second predetermined number or more of the stations among a plurality of stations for players to play games.

According to a sixth aspect of the present invention, there is provided a playing method of a gaming apparatus having the following structure.

That is, the playing method of a gaming apparatus according to the sixth aspect of the present invention is a playing method of a gaming apparatus comprising the steps of: (a) controlling rotation of a roulette wheel and launching of a ball by referring to a single control data, the single control data selected out of a plurality of control data for controlling the gaming apparatus so as to provide a relatively high weight on a probability that the ball is housed in any of the pockets constituting a single group, the single group belonging to a plurality of groups each of which consists of a first predeter-

mined number of pockets out of a plurality of pockets being included in the roulette wheel and being associated with respective numbers in advance, (b) counting the number of games played, (c) counting the number of high-probability bets, that is the number of games in which a bet is placed on any of the pockets belonging to a group having the relatively high ball-housing probability at a second predetermined number or more of the stations among a plurality of stations for players to play games, (d) calculating frequency of high-probability bets, that is frequency of games in which a bet is placed on any of the pockets belonging to a group having the relatively high ball-housing probability at the second predetermined number or more of the stations, based on the number of games and the number of high-probability bets, and (e) selecting another control data different from the single control data, out of the plurality of control data, to set the selected control data as a reference target, when the frequency of high-probability bets exceeds a predetermined frequency.

According to a seventh aspect of the present invention, there is provided a playing method of a gaming apparatus having the following structure.

That is, the playing method of a gaming apparatus according to the seventh aspect of the present invention is a playing method of a gaming apparatus comprising the steps of: (a) controlling rotation of a roulette wheel and launching of a ball by referring to a single control data, the single control data selected out of a plurality of control data for controlling the gaming apparatus so as to provide a relatively high weight on a probability that the ball is housed in any of the pockets constituting a single group, the single group belonging to a plurality of groups each of which consists of a first predetermined number of pockets out of a plurality of pockets being included in the roulette wheel and being associated with respective numbers in advance, (b) determining a number corresponding to one of the pockets with the ball housed therein as a winning number, and (c) selecting another control data different from the single control data, out of the plurality of control data, and setting the selected control data as a reference target, when a bet is placed on any of the pockets belonging to a group having the relatively high ball-housing probability at a second predetermined number or more of the stations among a plurality of stations for players to play games, and a prize is determined to be offered based on this bet and the determined winning number.

According to an eighth aspect of the present invention, there is provided a playing method of a gaming apparatus having the following structure.

That is, the playing method of a gaming apparatus according to the eighth aspect of the present invention is a playing method of a gaming apparatus comprising the steps of: (a) controlling rotation of a roulette wheel and launching of a ball by referring to a single control data, the single control data selected out of a plurality of control data for controlling the gaming apparatus so as to provide a relatively high weight on a probability that the ball is housed in any of the pockets constituting a single group, the single group belonging to a plurality of groups each of which consists of a first predetermined number of pockets out of a plurality of pockets being included in the roulette wheel and being associated with respective numbers in advance, (b) determining a number corresponding to one of the pockets with the ball housed therein as a winning number, (c) counting the number of games played, (d) counting the number of prize offering, that is the number of games in which a bet is placed on any of the pockets belonging to a group having the relatively high ball-housing probability at a second predetermined number or more of the stations among a plurality of stations for players

to play games, and a prize is offered based on this bet and the determined winning number, (e) calculating frequency of prize offering, that is frequency of games in which a bet is placed on any of the pockets belonging to a group having the relatively high ball-housing probability at the second predetermined number or more of the stations, and a prize is offered based on this bet and the determined winning number, and (f) selecting another control data different from the single control data, out of the plurality of control data, to set the selected control data as a reference target, when the frequency of prize offering exceeds a predetermined frequency.

BRIEF DESCRIPTION OF THE DRAWINGS

FIG. 1 is a plan view of a roulette device according to the first embodiment;

FIG. 2 is a view illustrating exemplary control data;

FIG. 3 is an external perspective view illustrating the general structure of a roulette gaming machine according to the first embodiment;

FIG. 4 is a view illustrating an exemplary image displayed to an image display device;

FIG. 5 is a block diagram illustrating the internal structure of the roulette gaming machine according to the first embodiment;

FIG. 6 is a schematic view illustrating a storage area of a ROM in the roulette gaming machine according to the first embodiment;

FIG. 7 is a schematic view illustrating a storage area of a RAM in the roulette gaming machine according to the first embodiment;

FIG. 8 is a block diagram illustrating the internal structure of the roulette device according to the first embodiment;

FIG. 9 is a schematic view illustrating a storage area of a ROM in the roulette device according to the first embodiment;

FIG. 10 is a block diagram illustrating the internal structure of a station according to the first embodiment;

FIG. 11 is a flow chart illustrating a game processing in the roulette gaming machine according to the first embodiment;

FIG. 12 is a flow chart illustrating another game processing in the roulette gaming machine according to the first embodiment;

FIG. 13 is a schematic view illustrating a storage area of a RAM in the roulette gaming machine according to the second embodiment;

FIG. 14 is a flow chart illustrating a game processing in the roulette gaming machine according to the second embodiment;

FIG. 15 is a flow chart illustrating another game processing in the roulette gaming machine according to the second embodiment; and

FIG. 16 is a flow chart illustrating a subroutine of a control data determination processing.

DESCRIPTION OF THE EMBODIMENTS

First Embodiment

FIG. 1 is a plan view of a roulette device according to the first embodiment. FIG. 2 is a view illustrating exemplary control data. FIG. 3 is an external perspective view illustrating the general structure of a roulette gaming machine according to the first embodiment. While the roulette gaming machine 1 is a standalone type gaming machine which is not connected to a network, the present invention can be applied to a gaming machine connected to a network.

As illustrated in FIG. 1, the roulette device 3 included in the roulette gaming machine 1 (see FIG. 3) includes a frame member 21 secured to a cabinet 2 (see FIG. 3), and a roulette wheel 22 which is rotatably housed and supported inside the frame member 21. On an upper surface of the roulette wheel 22, there are formed a large number of concave-shaped number pockets 23 (a total of 38 number pockets in the present embodiment). Further, on the upper surface of the roulette wheel 22 in the outer directions of the respective number pockets 23, there are formed number display plates 25 displaying respective numbers of "0", "00", and "1" to "36", in association with the respective number pockets 23.

A ball throwing port 36 is formed in the frame member 21. A ball throwing device 104 (see FIG. 8) is connected to the ball throwing port 36, so that a ball 27 can be thrown onto the roulette wheel 22 from the ball throwing port 36 by being driven by the ball throwing device 104. Further, the roulette device 3 is entirely covered with a hemispherical transparent acrylic cover member 28 (see FIG. 3) thereabove.

Below the roulette wheel 22, there is provided a wheel-driving motor 106 (see FIG. 8), so that the roulette wheel 22 is rotated by being driven by the wheel driving motor 106.

Further, metal plates (not illustrated) are mounted at predetermined intervals below the roulette wheel 22, and these metal plates are detected by a proximity sensor included in a pocket position detection circuit 107 (see FIG. 8), which enables detecting the positions of the number pockets 23.

The frame member 21 is gently inclined in an inward direction, and a guide wall 29 is formed at a middle position thereof. The guide wall 29 is for guiding the thrown ball 27 against a centrifugal force to cause the ball 27 to roll. As a rotation speed of the ball 27 decreases and, thus, the centrifugal force thereof decreases, the ball 27 rolls along the inclined surface of the frame member 21 and travels inwardly to reach the rotating roulette wheel 22. Then, the ball 27 which has rolled and reached the roulette wheel 22 passes over the number display plates 25 outside the still rotating roulette wheel 22 and then is housed in one of the number pockets 23. As a result, a ball sensor 105 (see FIG. 8) detects the number displayed to the number display plate 25 corresponding to the number pocket 23 housing the ball, and this number becomes a winning number.

Rotation of the roulette wheel 22 and launching of the ball 27 are performed based on control data.

As illustrated in FIG. 2, the control data includes motor driving time, ball initial speed, and launching delay time.

The motor driving time is for driving the wheel driving motor 106 (see FIG. 8). The roulette wheel 22 is rotated at a predetermined rotation speed by the wheel-driving motor 106 for a length of time corresponding to a motor driving time. Further, after the roulette wheel 22 is released from the driving by the wheel-driving motor 106, the rotation speed of the roulette wheel 22 gradually decreases and the roulette wheel 22 finally stops. Further, the ball initial speed is an initial speed for throwing the ball 27 from the ball throwing device 104. The launching delay time is a time since a predetermined number pocket 23 passes through a predetermined position until a ball is launched, during the rotation of the roulette wheel 22.

As illustrated in FIG. 1, the roulette wheel 22 is divided into 6 areas, which are areas A to F. Each area is constituted by 6 or 7 number pockets 23 adjacent to one another. The number of number pockets 23 constituting each area corresponds to a first predetermined number according to the present invention. The respective control data are determined so as to provide a higher weight on the probability that the ball 27 is housed in one of the areas A to F. For example, when the

rotation of the roulette wheel 22 and the launching of the ball 27 are controlled based on the control data “a motor driving time of 10 sec, a ball initial speed a and a launching delay time of 0,” the respective control data are determined so as to provide a higher weight on the probability that the ball 27 is housed in the area A.

In the present embodiment, the roulette wheel 22 rotates counterclockwise, and the ball 27 moves clockwise. For example, when the ball initial speed and the launching delay time are fixed, as the motor driving time is made longer, an area with a high probability of housing the ball 27 (hereinafter also referred to as a high probability area) is changed in the following order: A→B→C→D→E→F→A and so forth.

Further, for example, when the motor driving time and the launching delay time are fixed, as the ball initial speed is made higher, the high probability area is changed in the following order: A→B→C→D→E→F→A and so forth.

Moreover, for example, when the motor driving time and the ball initial speed are fixed, as the launching delay time is made longer, the high probability area is changed in the following order: A→B→C→D→E→F→A and so forth.

Accordingly, in the present invention, when the control data includes any one of data on wheel rotation control (motor driving time), data on timing for launching the ball (launching delay time), and data on the initial speed of the ball being launched (ball initial speed), a plurality of control data different in high probability area can be set, thereby providing different weights on the probability of each number pocket 23 housing the ball 27.

Further, in the present embodiment, when the initial speed is changed from an initial speed “a” to an initial speed “b”, from the initial speed “b” to an initial speed “c”, from the initial speed “c” to an initial speed “d” and so forth, the high probability area is shifted by one area (e.g. the area is shifted from the area A to the area B). Further, every time the launching delay time is made longer by 0.1 second, the high probability area is shifted by one area. Moreover, every time the motor driving time is made longer by 1 second, the high probability area is shifted by five areas. Therefore, by combination of these, it is possible to set a plurality of control data different in high probability areas, so as to provide different weights on the probability of the each number pocket 23 housing the ball 27.

As in the present embodiment, when the control data is data including the combination of the data on wheel rotation control (motor driving time), the data on timing for launching the ball (launching delay time), and the data on the initial speed of the ball being launched (ball initial speed), apparent variations with respect to the player (e.g. the rotating time of the roulette wheel 22 is long, the initial speed of the ball 27 is high) can be involved.

Friction at the rotational axial section of the roulette wheel 22, the surface shape of the roulette wheel 22 (e.g. depression or distortion), and the like may vary among the roulette gaming machines 1 due to a variety of factors in manufacturing thereof. Hence there is a case where, even when common control data is used in each of the roulette gaming machines 1, the areas where the ball 27 is finally housed vary among the roulette gaming machines 1. Therefore, the control data may be set such that, for example, after completion of the manufacturing, tests are conducted with a variety of parameters included in the control data being changed as appropriate, to organize statistics concerning which parameter may allow which area to have a high probability of housing the ball 27. Namely, the control data may vary among the roulette gaming machines 1.

Moreover, even when the areas that finally house the ball 27 vary among the roulette gaming machines 1, the common control data may be used in each of the roulette gaming machines 1. This is because the probability of housing the ball 27 in some area should just be relatively high based on the control data in each of the roulette gaming machines 1.

The control data to be a reference target is switched when the frequency of high-probability bets exceeds a predetermined frequency (for example, 0.5). The frequency of high-probability bets is calculated on the basis of the number of games and the number of high-probability bets. In the present embodiment, the frequency of high-probability bets is calculated as the ratio of the number of high-probability bets to the number of games. The term “the number of games” refers to the number of games which have been played. The term “the number of high-probability bets” refers to the number of games in which a bet is placed on pockets belonging to a high probability area at a number of stations equal to or more than a second predetermined number (6, in the present embodiment).

In the present embodiment, if at least a single bet is placed on a number included in a high probability area at a station 4, this station 4 is counted as a station 4 at which a bet has been placed on the high probability area (hereinafter, referred to as a high-probability bet), regardless of the number of bets. For example, at a single station 4, when a bet is placed on “9” included in the area A and on “16” included in the area E, if the area A is a high probability area, this single station 4 is counted as a station 4 at which a high-probability bet has been placed.

For example, when 10 games have been played and the number of high-probability bets is 3, the frequency of high-probability bets is 0.3.

In the present embodiment, there will be described a case where a game is played by using all the 12 stations 4. Namely, it is assumed that a game is played only when 12 players take part therein. However, in the present invention, even when not all the stations are used (when there are less than 12 players, in the present embodiment), a game may be played. In this case, the second predetermined number may be defined by the ratio of the second predetermined ratio relative to the number of the stations being used in a game (for example, a ratio of 0.5).

Further, in the present invention, a station refers to a device which enables a player to perform operations for betting currency values. In the present embodiment, the station is configured such that a player can make a bet by operating a touch panel 50 (see FIG. 10) provided in the front surface of an image display device 8 and medals are paid out from a medal payout port 9 (see FIG. 3) through a hopper 94 (see FIG. 10) being driven therein.

Further, in the present invention, the second predetermined number may be either 1 or equal to or more than 2.

While, in the example, there has been described a case where the areas A to F are constituted by 6 or 7 number pockets 23 adjacent to one another, there is no particular limitation on the number (first predetermined number) of pockets belonging to a single group, in the present invention. Further, the respective groups can be constituted by the same number of pockets or different numbers of pockets.

Further, while, in the example, there has been described a case where the number pockets 23 are divided into the 6 areas (groups), which are the areas A to F, the number of areas (groups) is not limited to 6 in the present invention.

In the example, there has been described a case where the areas A to F are not overlapped with one another. Namely, there has been described a case where the pockets belonging

to a single group do not belong to the other groups. However, the present invention is not limited thereto, and a single pocket can belong to a plurality of groups.

While, in the example, there has been described a case where a plurality of control data are provided in association with the respective areas (groups), it is necessary only that a plurality of control data are provided, but it is not necessary that they are associated with the respective areas (groups), in the present invention.

While, in the example, there has been described a case where the control data is constituted by motor driving time, ball initial speeds and launching delay time, the control data of the present invention is not limited thereto, but may be data including one of data relating to wheel rotation control (motor driving time), data relating to a timing of ball launching (launching delay time), and data relating to an initial speed for launching a ball (ball initial speeds), or a combination thereof.

Such data relating to wheel rotation control may be, for example, rotation speeds of the roulette wheel when it is driven by the motor, as well as motor driving time.

While, in the example, the case was described where the control data corresponds one-to-one to the area, e.g. control data with "the motor driving time: 10 sec, the ball initial speed: a, the launching delay time: 0" corresponds to the area A. However, the control data in the present invention is not limited thereto so long as the control data serves to perform control so as to provide different weights on the probability of each of the pockets housing the ball. For example, the control data may be data where the probability of the pocket housing the ball is fixed, the pocket belonging to each area (group), e.g., the probability that the number pocket 23 belonging to the area A houses the ball 27 is 70%, the probability that the number pocket 23 belonging to the area B houses the ball 27 is 20%, or the probability that the number pocket 23 belonging to the area C houses the ball 27 is 10%. In such a configuration, for example, a single group may be determined based on the above probabilities to control such that the pocket belonging to the determined group houses the ball.

Next, the structure of the roulette gaming machine 1 will be described.

As illustrated in FIG. 3, the roulette gaming machine 1 includes the cabinet 2 forming a main body, the roulette device 3 provided at a substantially center portion of the upper surface of the cabinet 2, a plurality of stations 4 (12 stations, in the present embodiment) installed around the roulette device 3 to surround the roulette device 3, and an electric lighting display portion 5 provided above the cabinet 2.

In the present embodiment, there will be described a case where the roulette gaming machine 1 includes 12 stations 4. However, the number of stations is not limited to 12, in the present invention.

The stations 4 include, at least, a medal insertion port 6 for inserting a currency value, a control portion 7 constituted by a plurality of control buttons and the like which enable a player to input predetermined commands, and an image display device 8 capable of displaying images relating to games. Further, the stations 4 receive betting operations by the player. The player can process games being deployed, by operating the touch panel, the control portion 7 and the like, while looking at the image being displayed to the image display device 8.

The currency values used for the roulette gaming machine 1 includes medal and valuable electronic information (for

example, credit). Here, the currency values are not particularly limited, and examples thereof include a coin, a bill, a token, and electronic money.

Further, medal payout ports 9 are provided in the side surfaces of the cabinet 2 in which the stations 4 are installed. Further, above the image display devices 8 in the respective stations 4, to the right thereof, there are provided speakers 10 for generating music, effect sounds and the like.

Above the image display devices 8 in the respective stations 4, there are provided WIN lamps 11. In the event of the occurrence of winning relating to numbers ("0", "00" or "1" to "36" in the present embodiment) on which the player betted at the station 4 during a game, the WIN lamp 11 in the winning station 4 is lighted. Further, during JP (jackpot) bonus games 15 for acquiring a jackpot (hereinafter, referred to as "JP"), in the event that a station 4 acquires a JP, the WIN lamp 11 in the station 4 which acquired the JP is similarly lighted. Further, the WIN lamps 11 are provided at positions viewable from all the installed stations 4 (12 stations, in the present embodiment), which enables other players playing games with the same roulette gaming machine 1 to recognize the WIN lamps 11 being lighted anytime.

Inside of each medal insertion port 6, there is provided a medal sensor (not illustrated) which distinguishes the currency value inserted from the medal insertion port 6, such as medals, and counts the inserted medals. Further, inside of each medal payout port 9, there is provided a hopper (not illustrated) which pays out predetermined numbers of medals from the medal payout port 9.

A server 13 is placed inside of a corner portion 12 positioned at a corner of the cabinet 2. The server 13 is housed within the corner portion 12 in general in order to prevent it from being operated by players, but a corner door 14 provided at the corner portion 12 can be opened using a key switch in order to enable operations of the server 13. Further, by operating the server 13, various types of setting can be made for the roulette gaming machine 1.

In the electric lighting display portion 5, there is provided a JP-value display portion 15 which displays the value of JP. 40 In the roulette gaming machine 10 according to the present embodiment, as will be described later, there are prepared 3 types of JP, i.e., "MEGA", "MAJOR" and "MINI". For the JP "MEGA", 0.15% of the credits betted during games at all the 12 stations 4 are cumulatively stored. For the JP "MAJOR", 0.20% of the betted credits are cumulatively stored. For the JP "MINI", 0.30% of the betted credits are cumulatively stored. Further, in the event that the player wins any one of the JP during JP bonus games which will be described later, credits corresponding to the cumulative value accumulated for the corresponding JP are paid out to a predetermined station 4. The JP-value display portion 15 displays the cumulative value for the JP "MEGA", out of the three types of JP. Further, the JP-value display portion 15 is provided at the top portion of the electric lighting display portion 5, which enables all players playing games at the stations 4 to view the content of the display thereon.

FIG. 4 is a view illustrating an exemplary image displayed to an image display device.

As illustrated in FIG. 4, during games, the image display device 8 displays, thereto, a BET screen 61 having a table-type betting board 60. The player can bet chips using his or her own credits, by operating the touch panel 50 (see FIG. 10) provided in the front surface of the image display device 8.

First, based on FIG. 4, there will be described the BET screen 61 which is displayed during games. In the table-type betting board 60 being displayed in the BET screen 61, 38 types of numbers "0", "00" and "1" to "36" are displayed and

11

arranged in a grid shape. Further, specific BET areas are similarly arranged in a grid shape, wherein the specific BET areas are for specifying “odd numbers”, “even numbers”, “the types of colors of the number display plates (red or black)”, “certain numerical ranges (for example, “1” to “12” and the like) so that chips can be betted thereon.

Under the table-type betting board 60, there are displayed a result history display portion 65, unit BET buttons 66, a payback result display portion 67, and a number-of-credit display portion 68.

The result history display portion 65 displays a list of winning numbers resulted from the previous games (in this case, “a single game” refers to a series of operations starting with betting by a player in any of the stations 4 and then throwing the ball 27 into the number pockets 23 and ending with paying back credits based on the winning number). In this case, when a single game ends, a new winning number is added and displayed to the top of the list, which enables recognizing the history of winning numbers resulted from up to 16 games.

Further, the unit BET buttons 66 are for betting chips on a BET area 72 (over a grid having a number or mark or over a line defining grids) specified by the player. The unit BET button 66 is constituted by four buttons, which are a 1-BET button 66A, a 5-BET button 66B, a 10-BET button 66C and a 100-BET button 66D.

At first, the player specifies a BET area 72 on which he or she desires to bet, with a cursor 70 which will be described later, by directly pushing it on the screen. By pushing the 1-BET button 66A at this state, the player can bet one chip at a time (i.e., every time the 1-BET button 66A is pushed with fingers or the like, the number of bets is increased in the order of “1”, “2”, “3” and so forth). By pushing the 5-BET button 66B, the player can bet five chips at a time (i.e., every time the 5-BET button 66B is pushed with fingers or the like, the number of bets is increased in the order of “5”, “10”, “15” and so forth). By pushing the 10-BET button 66C, the player can bet ten chips at a time (i.e., every time the 10-BET button 66C is pushed with fingers or the like, the number of bets is increased in the order of “10”, “20”, “30” and so forth). Further, by pushing the 100-BET button 66D, the player can bet chips 100 chips at a time (i.e., every time the 100-BET button 66D is pushed with fingers or the like, the number of bets is increased in the order of “100”, “200”, “300” and so forth).

The payback result display portion 67 displays the number of chips betted by the player and the number of paid-back credits in the previous game. In this case, the number of paid-back credits minus the number of betted chips indicates the number of credits that the player newly acquired in the previous game.

The number-of-credit display portion 68 displays the number of credits possessed by the current player. If chips are betted, the number of credits is decreased by an amount corresponding to the number of bets (1 bet corresponds to 1 credit). In the event of that winning relating to the betted chips occurs and credits are paid back, the number of credits is increased by the number of paid-back credits. Further, if, the number of credits possessed by the player becomes 0, the games end.

Further, above the table-type betting board 60, a BET time display portion 69 is provided. The BET time display portion 69 displays the remaining time during which the player can bet. The BET time display portion 69 displays “20” at the start of reception of betting operations, then decreases the number by one at every second and displays “0” at the end of reception of betting operations. Further, when the remaining betting

12

time for the player reaches 5 seconds at each station 4, the ball throwing device is driven to throw the ball 27 onto the roulette board.

Further, to the right of the BET-time display portion 69, there are provided a MEGA display portion 73 which displays the number of credits accumulated for the JP “MEGA” until the present time, a MAJOR display portion 74 which displays the number of credits accumulated for the JP “MAJOR” until the present time, and a MINI display portion 75 which displays the number of credits accumulated for the JP “MINI” until the present time. The MEGA display portion 73 displays a number of credits resulted from cumulatively accumulating 0.15% of the credits betted in every single game at all 12 stations 4. The MAJOR display portion 74 displays a number of credits resulted from cumulatively accumulating 0.20% of the betted credits. The MINI display portion 75 displays a number of credits resulted from cumulatively accumulating 0.30% of the betted credits. The MEGA display portion 73, the MAJOR display portion 74 and the MINI display portion 75 display numerical values which are common among all the stations 4. In the event that the player wins a JP during a JP bonus game, the credits for the JP won by the player are paid out, out of the three types of JP displayed to the display portions 73 to 75, and, after the paying out, the JP display portion displays an initial numerical value (i.e., 200 credits for “MINI”, 5000 credits for “MAJOR” and 50000 credits for “MEGA”).

Further, on the table-type betting board 60, the cursor 70 indicating the BET area 72 being currently selected by the player is displayed. Further, a chip mark 71 indicating the number of chips betted up to the present time and the BET area 72 is displayed, wherein the number displayed to the chip mark 71 indicates the number of betted chips. For example, as illustrated in FIG. 4, a “7” chip mark 71 placed-on the “18” grid indicates that 7 chips are being betted on the number “18”. Further, such a method for betting on only a single number is a betting method called “Straight Bet”.

Further, a “1” chip mark 71 placed at the intersection of the “5”, “6”, “8” and “9” grids indicates that all the four numbers are covered, meaning a single chip is being betted on the four numbers “5”, “6”, “8” and “9”. Further, such a method covering four numbers for betting on the four numbers is a betting method called “Corner Bet”.

As other betting methods, there are “Split Bet” which covers two numbers using the line between the two numbers so as to bet on two numbers; “Street Bet” which covers three numbers using an end of a lateral single row of numbers (a vertical single row, in FIG. 4) so as to bet on three numbers (for example, “13”, “14” and “15”); “Five Bet” which covers five numbers using the line between the numbers “00” and “3” so as to bet on five numbers “0”, “00”, “1”, “2” and “3”; “Line Bet” which covers six numbers using the space between two lateral rows of numbers (two vertical rows in FIG. 4) so as to bet on six numbers (for example, “13”, “14”, “15”, “16”, “17” and “18”); “Column Bet” which covers twelve numbers using a “2-to-1” grid so as to bet on twelve numbers; and “Dozen Bet” which covers twelve numbers using any of “1st-12”, “2nd-12” and “3rd-12” grids so as to bet on twelve numbers. Further, there is a method which covers 18 numbers so as to bet on 18 numbers, by specifying the 18 numbers from any of the colors of the number display plates (“red” or “black”), odd numbers or even numbers, and numbers equal to or less than 18 or numbers equal to or greater than 19, using 6 grids provided at the lowermost stage of the table-type betting board 60. In this case, these plurality of betting methods result in different credit payout values

(payout value ratios) per single chip, in the event of the occurrence of winning relating to betted chips.

When a player performs betting through the BET screen 61 having the above-mentioned configuration, the player specifies a BET area 72 (over a grid having a number or mark or over a line defining grids) on which he or she desires to bet, by directly pushing it on the screen with his or her finger. As a result, the cursor 70 moves to the specified BET area 72.

Thereafter, by pushing each unit button (the 1-BET button 66A, the 5-BET button 66B, the 10-BET button 66C and the 100-BET button 66D), out of the unit BET buttons 66, a number of chips corresponding to the number of units are betted on the specified BET area 72. For example, by pushing the 10-BET button 66C four times, pushing the 5-BET button 66B a single time and pushing the 1-BET button 66A three times, it is possible to bet a total of 48 chips.

FIG. 5 is a block diagram illustrating the internal structure of the roulette gaming machine according to the first embodiment.

As illustrated in FIG. 5, the roulette gaming machine 1 is constituted by the server 13 and the plurality of stations 4 (12 stations in the present embodiment) connected to the server 13, wherein the roulette device 3 and the electric lighting display portion 5 are connected to the server 13. Further, the internal structures of the roulette device 3 and the stations 4 will be described in detail later.

The server 13 includes a server-controlling portion 80 comprised of a server-controlling CPU 81 which controls the entire server 13, a ROM 82, and a RAM 83. The server-controlling portion 80 corresponds to a controller in the present invention. Further, the server-controlling CPU 81 includes a timer 84, a liquid crystal display 32 connected through a liquid crystal driving circuit 85, and a key board 33.

The server-controlling CPU 81 conducts various types of processing, based on input signals supplied from the respective stations 4 and data and programs stored in the ROM 82 and the RAM 83. Then, based on the results thereof, the server-controlling CPU 81 transmits command signals to the stations 4, to control the respective stations 4 in an initiative manner. Particularly, the server-controlling CPU 81 transmits control signals to the roulette device 3 to control the launching of the ball 27 and the rotation of the roulette wheel 22.

The ROM 82, which is constituted by, for example, a semiconductor memory, stores programs for realizing basic functions of the roulette gaming machine 1, programs for setting and managing annunciation of maintenance times and conditions to be announced, programs for controlling, in an initiative manner, payout value ratios for roulette games (the numbers of credits to be paid out for winning per single chip) and the respective stations 4, and the like.

On the other hand, the RAM 83 temporarily stores information on betted chips supplied from the respective stations 4, winning numbers of the roulette device 3 determined by a sensor, JP values accumulated until the present time, data about the results of processing executed by the server-controlling CPU 81, and the like.

Further, the timer 84 for use in time measurement is connected to the server-controlling CPU 81.

Time information from the timer 84 is transmitted to the server-controlling CPU 81, which controls rotation operation on the roulette wheel 22 and throwing in of the ball 27, based on the time information from the timer 84, as will be described later.

Further, the electric lighting display portion 5 (see FIG. 3) is connected to the server-controlling CPU 81. Further, the server-controlling CPU 81 controls light emission from LEDs and the like for performing illumination effects and

also for displaying predetermined characters and the like to the electric lighting display portion 5. Further, the server-controlling CPU 81 especially causes the JP-value display portion 15 in the electric lighting display portion 5 to display the value of a JP (JP "MEGA" in the present embodiment) which has been accumulated until the present time.

FIG. 6 is a schematic view illustrating the storage area of the ROM in the roulette gaming machine according to the first embodiment.

As illustrated in FIG. 6, the ROM 82 is provided with a payout value credit storage area 82A which stores payout value ratios relating to games. Further, as payout value ratios for the respective BET areas 72 in the BET screen 61 stored in the payout value credit storage area 82A, there have been stored, in advance, predetermined ratios "×2" to "×36", depending on the types of betting methods (such as "Straight Bet", "Corner Bet", "Split Bet" and the like).

FIG. 7 is a schematic view illustrating the storage area of the RAM in the roulette gaming machine according to the first embodiment.

As illustrated in FIG. 7, the RAM 83 is provided with a BET information storage area 83A which stores information on betting by players currently playing games, a winning-number storage area 83B which stores a winning number of the roulette device 3 determined by the ball sensor 105, a "MINI" JP cumulative storage area 83C which stores the number of credits cumulatively accumulated for the JP "MINI", a "MAJOR" JP cumulative storage area 83D which stores the number of credits cumulatively accumulated for the JP "MAJOR", a "MEGA" JP cumulative storage area 83E which stores the number of credits cumulatively accumulated for the JP "MEGA", a number-of-games storage area 83F which stores the number of games, and a number-of-high-probability-bets storage area 83G which stores the number of high-probability bets. Further, more specifically, the betting information is information on betting performed through the stations 4, such as BET areas 72 (see FIG. 4) specified on the BET screen 61, the numbers of betted chips (the numbers of bets), and the types of betting methods.

FIG. 8 is a block diagram illustrating the internal structure of the roulette device according to the first embodiment.

As illustrated in FIG. 8, the roulette device 3 includes a control portion 109, the pocket position detection circuit 107, the ball throwing device 104, the ball sensor 105, the wheel driving motor 106 and a ball collecting device 108.

The control portion 109 includes a CPU 101, a ROM 102 and a RAM 103. The CPU 101 controls the launching of the ball 27 and the rotation of the roulette wheel 22, based on control signals supplied from the server 13 and data and programs stored in the ROM 102 and the RAM 103.

FIG. 9 is a schematic view illustrating the storage area of the ROM in the roulette device according to the first embodiment.

As illustrated in FIG. 9, the ROM 102 is provided with a control data storage area 102A which stores control data having the structure described with reference to FIG. 2.

The pocket position detection circuit 107 includes a proximity sensor and detects the position of the roulette wheel 22 based on the presence or absence of detections of a metal plate mounted to the roulette wheel 22.

The ball throwing device 104 is a device for throwing the ball 27 onto the roulette wheel 22 through the ball throwing port 36 (see FIG. 1). The ball throwing device 104 throws the ball 27 at an initial speed defined by the control data. Further, the ball throwing device 104 throws the ball 27 at timing based on a launching delay time defined by the control data. Namely, the ball throwing device 104 throws the ball 27 after

the elapse of the launching delay time since the pocket position detection circuit **107** detected a predetermined number pocket **23** (for example, "00") passing a predetermined position (for example, the position at the front of the ball throwing port **36**).

The ball sensor **105** is a device for determining which number pocket **23** the ball **27** has been housed in.

The wheel driving motor **106** is for rotating the roulette wheel **22** and stops the driving of the motor after the elapse of a motor driving time defined by the control data since the start of the driving thereof.

The ball collecting device **108** is a device for collecting the ball **27** thrown onto the roulette wheel **22** after the end of games.

FIG. 10 is a block diagram illustrating the internal structure of a station according to the first embodiment. Further, the twelve installed stations **4** have basically the same structure and, therefore, a single station **4** will be exemplarily described, hereinafter.

As illustrated in FIG. 10, the station **4** includes a station control portion **90** constituted by a station-controlling CPU **91**, a ROM **92** and a RAM **93**. The ROM **92** is constituted by, for example, a semiconductor memory or the like and stores programs for realizing basic functions of the station **4**, other programs of various types necessary for controlling the station **4**, data tables and the like. Further, the RAM **93** is a memory for temporarily storing various types of data resulted from calculations by the station-controlling CPU **91**, the number of credits currently possessed by the player (accumulated in the station **4**), the condition of betting of chips by the player, and the like.

Further, a BET confirmation button **47**, a payback button **48** and a help button **49**, which are provided in the control portion **7** (see FIG. 3), are connected to the station-controlling CPU **91**.

The BET confirmation button **47** is to be pushed for confirming betting after betting operations through the image display device **8**.

The payback button **48** is to be generally pushed at the end of games. When the payback button **48** is pushed, a number of medals corresponding to the credits acquired in games and the like and currently possessed by the player (a single medal for a single credit, in general) are paid out from the medal payout port **9**.

The help button **49** is to be pushed when the game operating method or the like is unknown. Immediately after the help button **49** is pushed, a help screen describing information on various types of operations is displayed to the image display device **8**.

The station-controlling CPU **91**, based on operation signals issued by pushing respective buttons and the like, controls the station **4** for conducting various types of operations corresponding to the operation signals. More specifically, the station-controlling CPU **91** conducts various types of processing, based on input signals that the control portion **7** supplies thereto on receiving inputs of operations by the player, and data and programs stored in the ROM **92** and the RAM **93**. Then, the station-controlling CPU **91** transmits the result of such processing to the server-controlling CPU **81**.

Further, the station-controlling CPU **91**, on receiving command signals from the server-controlling CPU **81**, controls its peripheral devices constituting the station **4** for processing games in the station **4**. Further, the station-controlling CPU **91** conducts various types of processing, based on input signals that the control portion **7** supplies thereto on receiving inputs of operations by the player, and data and programs stored in the ROM **92** and the RAM **93**, and then controls its

peripheral devices constituting the station **4** for processing games in the station **4**, based on the result of such processing, depending on the contents of processing.

Further, a hopper **94** is connected to the station-controlling CPU **91**. The hopper **94** pays out predetermined numbers of medals from the medal payout port **9** (see FIG. 3), according to command signals from the station-controlling CPU **91**.

Further, the image display device **8** is connected to the station-controlling CPU **91** through a liquid crystal driving circuit **95**. The liquid crystal driving circuit **95** includes a program ROM, an image ROM, an image-controlling CPU, a work RAM, a VDP (Video Display Processor) and a video RAM. The program ROM stores image-controlling programs relating to the display on the image display device **8**, and various types of selection tables. The image ROM stores, for example, dot data for use in forming images to be displayed to the image display device **8**. The image-controlling CPU is for determining images to be displayed to the image display device **8**, out of the dot data pre-stored in the image ROM, according to the image-controlling programs pre-stored in the program ROM, based on parameters set in the station-controlling CPU **91**. The work RAM is formed as a temporal storage device for use in executing the image-controlling programs with the image-controlling CPU. The VDP creates images corresponding to the content of display determined by the image-controlling CPU and outputs them to the image display device **8**. Further, the video RAM is formed as a temporal storage device for use in creating images with the VDP.

Further, the touch panel **50** is provided in the front surface of the image display device **8** as previously described, and information on operations on the touch panel **50** is transmitted to the station-controlling CPU **91**. On the touch panel **50**, the player performs operations for betting chips through the BET screen **61**. More specifically, the touch panel **50** is operated in selecting BET areas **72**, operating the unit BET buttons **66** and the like, and information on such operations is transmitted to the station-controlling CPU **91**. Then, based on such information, information on the betting by the current player (i.e., information on the BET areas specified on the BET screen **61** and the number of chips betted thereon) is stored in the RAM **93** anytime. Further, the betting information is transmitted to the server-controlling CPU **81** and is stored in the BET information storage area of the RAM **83**.

Further, a sound output circuit **96** and a speaker **10** are connected to the station-controlling CPU **91**, wherein the speaker **10** generates various types of effect sounds when various types of effects are conducted based on output signals from the sound output circuit **96**.

Further, a medal sensor **97** is connected to the station-controlling CPU **91**. The medal sensor **97** detects medals inserted from the medal insertion port **6** (see FIG. 3), calculates the value of the inserted medals and transmits the result to the station-controlling CPU **91**. The station-controlling CPU **91**, based on the transmitted signals, increases the number of credits possessed by the player which is stored in the RAM **93**.

The WIN lamp **11** is connected to the station-controlling CPU **91**. The station-controlling CPU **91** lights the WIN lamp **11** in predetermined colors, in the event of the occurrence of winning relating to chips betted on the BET screen **61** or the winning of JP.

Hereinafter, based on FIG. 11 and FIG. 12, there will be described server-side game processing which is conducted by the server-controlling CPU **81** included in the roulette gaming machine **1** according to the present embodiment, and station-side game processing which is conducted by the station-

controlling CPU 91. FIG. 11 and FIG. 12 are flow charts illustrating game processing in the roulette gaming machine according to the present embodiment.

First, the station-side game processing will be described, based on FIG. 11 and FIG. 12.

At first, in step S11, the station-controlling CPU 91 determines whether or not medals or coins have been inserted by the player, based on detection signals from the medal sensor 97. If no medal or coin has been inserted (step S11: NO), the station-controlling CPU 91 waits for medals or coins to be inserted. On the other hand, if medals or coins have been inserted (step S11: YES), the processing proceeds to step S12.

In step S12, the station-controlling CPU 91 stores, in the RAM 93, an amount of credit data corresponding to the number of inserted medals or coins. Next, in step S13, the station-controlling CPU 91 transmits, to the server 13, a medal detection signal indicative of the presence of insertion of medals or coins.

Next, in step S14, the station-controlling CPU 91 causes the image display device 8 in the station 4 to display the BET screen 61 illustrated in FIG. 4.

Next, in step S15, the station-controlling CPU 91 starts measurement of a betting time period during which the player can bet chips.

Then, the player taking part in the game can bet his or her own chips on a BET area 72 relating to a winning number that he or she predicts, by operating the touch panel 50, during the betting time period during which betting can be received (see FIG. 4). Betting methods using the BET screen 61 have been already described in detail, and description thereof is not repeated.

Further, the player is allowed to take part in a game halfway therethrough after the start of the betting time period, and up to 12 players can play games with the roulette gaming machine 1 according to the present embodiment. Further, in cases where a current game is played subsequently to the previous game, the reception of betting operations is started immediately after the end of the previous game.

Next, in step S16, on receiving a betting-time-period end signal indicative of the end of the betting time period from the server-controlling CPU 81, the station-controlling CPU 91 causes the image display device 8 in the station 4 to display an image indicative of the end of the betting time period, and ends the reception of betting operations through the touch panel 50 (step S17). Thereafter, the station-controlling CPU 91 transmits information on the betting that the player performed at the station 4 (i.e., information on the specified BET area 72, the number of chips betted on the specified BET area 72 [i.e., the number of bets]) (step S18).

Next, in step S19, the station-controlling CPU 91 receives, from the server 13, the result of JP-bonus-game determination processing conducted by the server-controlling CPU 81, which will be described later. The result of JP-bonus-game determination includes the result of determination as to whether or not a predetermined JP bonus game should be generated at each station 4, the result of determination as to which station 4 out of the 12 stations 4 should win a JP (or as to whether all the stations 4 should not win the JP) if a JP bonus game should be generated, the result of determination as to which JP ("MEGA", "MAJOR" or "MINI") should be generated if a JP should be generated, and the like.

Next, in step S20 in FIG. 12, the station-controlling CPU 91 determines whether or not a JP bonus game should be generated, based on the result of the JP-bonus-game determination processing which was received in step S19. If the station-controlling CPU 91 determines that a JP bonus game should be generated at this station 4, the station-controlling

CPU 91 executes a predetermined selectable JP bonus game relating to acquisition of JPs and causes the image display device 8 to display the result of the game (i.e., whether or not a JP was acquired), based on the result of determination received in step S19.

If the station-controlling CPU 91 determines in step S20 that no bonus game should be generated at this station 4, or after the processing in step S21, the station-controlling CPU 91 receives the result of credit payout transmitted from the server-controlling CPU 81 (step S22). The result of credit payout is constituted by the result of payout in games and the result of JP payout in JP bonus games.

Next, in step S23, the station-controlling CPU 91 pays out credits, based on the result of payout received in step S22.

More specifically, the station-controlling CPU 91 stores, in the RAM 93, an amount of credit data corresponding to the payout value of the game and, also, stores therein, an amount of credit data corresponding to the JP payout value accumulated until the present time in cases where a JP bonus game was generated and the present station 4 won a JP. Then, if the payout button 48 is pushed, a number of medals corresponding to the number of credits currently stored in the RAM 93 (a single medal corresponds to a single credit, in general) are paid out from the medal payout port 9.

If a game is continuously played at one of the stations 4 thereafter, the processing returns to step S14, then starts the betting time period again and enters the next game.

On the other hand, if the game is ended at all the stations 4, the game processing ends.

Next, based on FIG. 11 and FIG. 12, the server-side game processing will be described.

At first, in step S101, the server-controlling CPU 81 determines whether or not medals or coins have been inserted by the player, on receiving medal detection signals transmitted from the station-controlling CPU 91. In the roulette gaming machine 1 according to the present embodiment, if medals or coins are inserted at one of the stations 4, the station-controlling CPU 91 in the station 4 at which the medals or coins have been inserted transmits a medal detection signal to the server-controlling CPU 81.

Next, the server-controlling CPU 81 starts measurement of a betting time period, at the time point when the player who first takes part in the game inserts medals or coins (step S102). The betting time period is a time period during which players can perform inputs for betting. Players taking part in the game can bet their own chips on BET areas 72 relating to winning numbers they predict, by operating the touch panel 50 during the betting time period.

Next, in step S103, the server-controlling CPU 81 determines whether or not the remaining betting time period has reached 5 seconds. Further, the remaining betting time period is displayed to the BET time display portion 69 (see FIG. 4). If it is determined that the remaining betting time period has not reached 5 seconds, the processing is returned to step S103. On the other hand, if it is determined that the remaining betting time period has reached 5 seconds, the processing shifts to step S104.

In step S104, the server-controlling CPU 81 transmits a control signal for starting an operation of the roulette device 3, to the CPU 101 in the roulette device 3. The CPU 101, on receiving the control signal, refers to the control data stored in the ROM 102 and controls operations as follows.

First, the CPU 101 drives the wheel driving motor 106 to rotate the roulette wheel 22, only during a motor driving time defined by the control data.

Then, after the elapse of a predetermined time period (for example, 20 seconds) since the start of the rotation of the

roulette wheel 22, the CPU 101 throws the ball 27 after the elapse of a launching delay time since it detected a detection signal from the pocket position detection circuit 107. At this time, the ball is thrown at an initial speed defined by the control data.

As control data to be referred by the CPU 101, single control data has been pre-set as a reference target, at the time of activation of the roulette gaming machine 1. Further, when another control data is set as the reference target, this another control data is referred to as the reference target by the CPU 101.

Next, in step S105, the server-controlling CPU 81 determines whether or not the betting time period has ended. If the server-controlling CPU 81 determines that the betting time period has not ended, it waits for the end of the betting time period.

On the other hand, if the server-controlling CPU 81 determines that the betting time period has ended, the server-controlling CPU 81 transmits a betting-time-period end signal indicative of the end of the betting time period, to the station-controlling CPU 91 (step S106).

Next, in step S107, the server-controlling CPU 81 receives, from the station-controlling CPU 91, information on the betting that the player performed at each station 4 (i.e., information on the specified BET area 72, the number of chips betted on the specified BET area 72 [i.e., the number of bets] and the betting method) and stores it in the BET information storage area 83A in the RAM 83.

Next, in step S108, the server-controlling CPU 81 adds 1 to the number of games stored in the number-of-games storage area 83F in the RAM 83 and stores the resultant number therein.

Next, in step S109, the server-controlling CPU 81 cumulatively adds a number of credits corresponding to 0.30% of the sum of the credits betted at all the stations 4, which were received in step S107, to the JP value stored in the "MINI" JP cumulative storage area 83C in the RAM 83. Further, the server-controlling CPU 81 cumulatively adds a number of credits corresponding to 0.20% of the sum of the credits to the JP value stored in the "MAJOR" JP cumulative storage area 83D in the RAM 83. Further, the server-controlling CPU 81 cumulatively adds a number of credits corresponding to 0.15% of the sum of the credits to the JP value stored in the "MEGA" JP cumulative storage area 83E in the RAM 83. Further, based on these JP values, the server-controlling CPU 81 updates the displays on the JP-value display portion 15, the MEGA display portion 73, the MAJOR display portion 74 and the MINI display portion 75.

Next, in step S110, the server-controlling CPU 81 conducts JP-bonus-game determination processing. In this processing, using random numbers sampled by a sampling circuit and the like, the server-controlling CPU 81 determines whether or not a JP bonus game should be generated at each station 4, determines which station 4 out of the 12 stations 4 should win a JP (or whether all the stations 4 should not win a JP) if a JP bonus game should be generated, and also determines which JP ("MEGA", "MAJOR" or "MINI") should occur if a JP should be generated.

Next, in step S111, the server-controlling CPU 81 transmits the result of JP bonus game determination to each station 4, based on the processing in step S110.

Next, in step S112 in FIG. 12, the server-controlling CPU 81 determines whether or not a high-probability bet has been placed at the number of stations 4 equal to or greater than a second predetermined number.

More specifically, at first, the server-controlling CPU 81 extracts information on the BET areas 72 specified by the

respective stations 4, from the betting information stored in the BET information storage area 83A in the RAM 83. Based on the information, the server-controlling CPU 81 counts the number of stations 4 which specified BET areas 72 including numbers belonging to the high probability area corresponding to the currently-set control data and determines whether or not the counted number is equal to or greater than the second predetermined number (6, in the present embodiment).

If the server-controlling CPU 81 determines that a high-probability bet has not been placed at the number of stations 4 equal to or greater than the second predetermined number, the processing shifts to step S114.

On the other hand, if the server-controlling CPU 81 determines that a high-probability bet has been placed at the number of stations 4 equal to or greater than the second predetermined number, the server-controlling CPU 81 adds 1 to the number of high-probability bets stored in the number-of-high-probability-bets storage area 83G in the RAM 83 and stores the resultant number therein (step S113).

Next, in step S114, the server-controlling CPU 81 determines whether or not the frequency of high-probability bets is greater than a predetermined frequency (0.5, in the present embodiment).

More specifically, the server-controlling CPU 81 determines whether or not the number of high-probability bets divided by the number of games is greater than 0.5.

If the server-controlling CPU 81 determines that the frequency of high-probability bets is equal to or less than the predetermined frequency, the processing shifts to step S117.

On the other hand, if the server-controlling CPU 81 determines that the frequency of high-probability bets is greater than the predetermined frequency, the server-controlling CPU 81 determines control data, in step S115.

More specifically, the server-controlling CPU 81 instructs the CPU 101 in the roulette device 3 to switch the control data. On receiving the instruction, the CPU 101 performs random number sampling, and based on the acquired random number, the CPU 101 selects control data different from the control data currently set as a reference target, out of the plurality of control data stored in the ROM 102 and sets the selected control data as a reference target.

Next, in step S116, the server-controlling CPU 81 clears the number of games and the number of high-probability bets. Namely, the server-controlling CPU 81 restores both the number of games stored in the number-of-games storage area 83F in the RAM 83 and the number of high-probability bets stored in the number-of-high-probability-bets storage area 83G to an initial value of 0.

Next, in step S117, the server-controlling CPU 81 transmits a control signal to the roulette device 3 to drive the ball sensor 105, thereby determining which number is associated with the number pocket 23 in which the ball 27 has been housed.

Next, the server-controlling CPU 81 determines whether or not winning relating to the chips betted at each station 4 has occurred, from the betting information on each station 4 which was received in step S117 and the type of the pocket determined in step S111 (step S118).

Next, in step S119, the server-controlling CPU 81 conducts a payout value calculation processing. In the payout value calculation processing, the server-controlling CPU 81 recognizes the winning chips betted on the winning number at each station 4 and calculates the sum of the payout value of credits to be paid out for each station 4, using the payout value ratios for the respective BET areas 72 (i.e., the numbers of credits to

be paid out for a single chip [1 bet]) stored in the payout value credit storage area **82A** in the ROM **82**.

Next, in step **S120**, the server-controlling CPU **81** conducts processing for transmitting the result of credit payout in games based on the payout value calculation processing in step **S119** and the result of JP payout based on the JP-bonus-game determination processing in step **S110**. More specifically, the server-controlling CPU **81** issues credit data corresponding to the amount of payout values resulted from games to the station-controlling CPU **91** in the station **4** which won the games. Further, when a JP is generated, the server-controlling CPU **81** further issues credit data corresponding to the JP value accumulated until the present time.

Next, in step **S121**, the server-controlling CPU **81** transmits a control signal to the roulette device **3** to drive the ball collecting device **108** provided under the roulette wheel **22** for collecting the ball **27** thrown onto the roulette wheel **22**. The collected ball **27** will be thrown into the roulette wheel **22** in the roulette device **3** again in subsequent games.

After the processing in step **S121**, the present subroutine ends.

As described above, the roulette gaming machine **1** according to the first embodiment includes the roulette wheel **22** including the plurality of number pockets **23** which have been associated with respective numbers in advance. Further, the roulette gaming machine **1** includes the ROM **102** (memory) which stores a plurality of control data for controlling the roulette gaming machine **1** so as to provide a higher weight on a probability that the ball **27** is housed in any of the number pockets **23** constituting a single area, the single area belonging to the plurality of areas (groups) each of which consists of 6 or 7 pockets of the number pockets **23**, and the plurality of control data associated with each of the areas. Further, the roulette gaming machine **1** comprises the plurality of stations **4** which enable players to play games. Further, the roulette gaming machine **1** includes the server-controlling portion **80** (controller) which refers to a single control data and controls the rotation of the roulette wheel **22** and the launching of the ball **27**. Further, the server-controlling portion **80** counts the number of games which has been played. Further, the server-controlling portion **80** counts the number of high-probability bets, which indicates the number of games in which a bet is placed on any of the number pockets **23** belonging to the area having the above-mentioned relatively high ball-housing probability at a second predetermined number or more of the stations **4** among the above-mentioned plurality of stations **4**. Further, the server-controlling portion **80** calculates the frequency of high-probability bets, that is frequency of games in which a bet is placed on any of the number pockets **23** belonging to a group having the above-mentioned relatively high ball-housing probability at the second predetermined number or more of the stations **4**, based on the above-mentioned number of games and the above-mentioned number of high-probability. If the above-mentioned frequency of high-probability bets exceeds a predetermined frequency, the server-controlling portion **80** selects another control data different from the above-mentioned single control data, out of the plurality of control data, to set the selected control data as a reference target.

In the present embodiment, the control data is switched if the ratio of the number of games in which a bet is placed on a high probability area at a number of stations **4** equal to or more than the second predetermined number relative to the number of games played exceeds a predetermined frequency. However, in the present invention, the condition to be satisfied for switching the control data is not limited to this example. For example, the control data may be switched

when a bet is placed on the high probability area at a number of stations **4** equal to or more than the second predetermined, regardless of the frequency of high-probability bets.

Further, in the present embodiment, if at least a single bet is placed on a number included in a high probability area at a station **4**, the station **4** is counted as a station **4** at which a bet has been placed on the high probability area, regardless of the number of bets. However, the present invention is not limited to this example. For example, if the number of bets placed on a number not belonging to the high probability area is more than the number of bets placed on a number belonging to the high probability area at a station, this station may not be counted as a station at which a bet has been placed on the high probability area.

In the present embodiment, there has been described a case where a game in which a bet is placed on a high probability area at a number of stations **4** equal to or more than the second predetermined number is counted as a number of high-probability bet, regardless of at which station **4** the bet has been placed. However, the present invention is not limited thereto, and a case where a game in which a bet is placed on a high probability area at a number of stations equal to or more than the second predetermined number, out of a predetermined plurality of stations, may be counted as a number of high-probability bet.

Second Embodiment

Next, there will be described a roulette gaming machine **30** according to a second embodiment. In the following description, components corresponding to those of the roulette gaming machine according to the first embodiment will be designated by the same reference characters.

The roulette gaming machine according to the second embodiment has an external view, a circuit structure and the like which are similar to those of the roulette gaming machine **1** according to the first embodiment and, also, displays images similar to those of the roulette gaming machine **1** according to the first embodiment. Therefore, description thereof is not repeated.

In the present embodiment, if the high-probability bet winning frequency exceeds a predetermined frequency (for example, 0.3), the control data to be a reference target is switched. The high-probability bet winning frequency is calculated based on the number of winnings of high-probability bets and the number of games. The term "the number of winnings of high-probability bets" refers to the number of games in which a high-probability bet is placed at a number of stations **4** equal to or more than a second predetermined number (for example, 6) and, also, the high-probability bet is won at a number of stations **4** equal to or more than the third predetermined number (for example, 6). The third predetermined number is a number equal to or smaller than the second predetermined number.

For example, when 20 games have been played and the number of winnings of high-probability bets is 4, the high-probability bet winning frequency is 0.2.

The number of winnings of high-probability bets corresponds to the number of prize offering according to the present invention, and the high-probability bet winning frequency corresponds to the frequency of prize offering according to the present invention.

FIG. 13 is a schematic view illustrating the storage area of the RAM in the roulette gaming machine according to the second embodiment. A RAM **200** is included in the server-controlling portion **80** of the roulette gaming machine **1** according to the present embodiment.

As illustrated in FIG. 13, the RAM 200 comprises a BET information storage area 200A which stores information on betting by players currently playing games, a winning-number storage area 200B which stores a winning number of the roulette device 3 determined by the ball sensor 105, a "MINI" JP cumulative storage area 200C which stores the number of credits cumulatively accumulated for the JP "MINI", a "MAJOR" JP cumulative storage area 200D which stores the number of credits cumulatively accumulated for the JP "MAJOR", a "MEGA" JP cumulative storage area 200E which stores the number of credits cumulatively accumulated for the JP "MEGA", a number-of-games storage area 200F which stores the number of games, and a number-of-winnings-of-high-probability-bets storage area 200G which stores the number of winnings of high-probability bets.

Hereinafter, there will be described server-side game processing which is conducted by the server-controlling CPU 81 included in the roulette gaming machine 1 according to the present embodiment, and station-side game processing which is conducted by the station-controlling CPU 91. FIG. 14 and FIG. 15 are flow charts illustrating game processing in the roulette gaming machine according to the second embodiment.

The station-side game processing (processing in steps S201 to S213) is the same as the processing in steps S11 to S23 in the station-side game processing according to the first embodiment (see FIG. 11 and FIG. 12), and description thereof is not repeated.

Next, the server-side game processing will be described.

The processing in steps S301 to S311 is the same as the processing in steps S101 to S111 in the server-side game processing according to the first embodiment (see FIG. 11 and FIG. 12), and description thereof is not repeated.

In step S312, the server-controlling CPU 81 transmits a control signal to the roulette device 3 to drive the ball sensor 105, thereby determining which number is associated with the number pocket 23 housing the ball 27.

Next, in step S313, the server-controlling CPU 81 determines whether or not winning relating to the chips betted at each station 4 has occurred, from the betting information about each station 4 which was received in step S307 and the type of the pocket determined in step S312.

Next, in step S314, the server-controlling CPU 81 conducts control-data determination processing. This processing will be described in detail later, with reference to FIG. 16.

Next, in step S315, the server-controlling CPU 81 conducts payout value calculation processing. This processing is the same as the processing in step S119 in FIG. 12 and is not repeated.

Next, in step S316, the server-controlling CPU 81 conducts processing for transmitting the result of credit payout in games based on the payout value calculation processing in step S315 and the result of JP payout based on the JP-bonus-game determination processing in step S310.

Next, in step S317, the server-controlling CPU 81 transmits a control signal to the roulette device 3 to drive the ball-collecting device 108 provided under the roulette wheel 22 for collecting the ball 27 on the roulette wheel 22. The collected ball 27 will be thrown onto the roulette wheel 22 in the roulette device 3 again in the subsequent games.

After the processing in step S317, the present subroutine ends.

FIG. 16 is a flow chart illustrating the subroutine of the control data determination processing which is conducted in step S314 in FIG. 15.

In step S401, the server-controlling CPU 81 determines whether or not a high-probability bet is placed at a number of

stations 4 equal to or more than a second predetermined number (6, in the present embodiment). This processing is the same as the processing in step S112 in FIG. 12 and will not be repeated.

5 If the server-controlling CPU 81 determines that a high-probability bet is not placed at a number of stations 4 equal to or more than the second predetermined number, the processing shifts to step S405.

On the other hand, if the server-controlling CPU 81 determines that a high-probability bet is placed at a number of stations 4 equal to or more than the second predetermined number, then the server-controlling CPU 81 determines, in step S402, whether or not the pocket with the ball housed therein determined in step S312 in FIG. 15 is a pocket belonging to the high probability area corresponding to the control data currently set as the reference target.

If the server-controlling CPU 81 determines that the pocket with the ball housed therein is not a pocket belonging to the high probability area, the processing shifts to step S405.

20 On the other hand, if the server-controlling CPU 81 determines that the pocket with the ball housed therein is a pocket belonging to the high probability area, then the server-controlling CPU 81 determines whether or not the number of players who won their bets (hereinafter, referred to as winning players) is equal to or more than a third predetermined number (6, in the present embodiment), based on the result of determination of winning in step S313 in FIG. 15 (step S403).

If it is determined that the number of winning players is not equal to or more than the third predetermined number, the processing shifts to step S405.

30 On the other hand, if the server-controlling CPU 81 determines that the number of winning players is equal to or more than the third predetermined number, the server-controlling CPU 81 adds 1 to the number of winnings of high-probability bets stored in the number-of-winnings-of-high-probability-bets storage area 200G in the RAM 200 and stores the resultant number therein.

35 Next, in step S405, the server-controlling CPU 81 determines whether or not the high-probability bet winning frequency is greater than a predetermined frequency (0.3, in the present embodiment). Namely, the server-controlling CPU 81 determines whether or not the number of winnings of high-probability bets divided by the number of games is greater than 0.3.

45 If it is determined that the high-probability bet winning frequency is equal to or smaller than the predetermined frequency, the present subroutine ends.

On the other hand, if it is determined that the high-probability bet winning frequency is greater than the predetermined frequency, then the server-controlling CPU 81 determines control data, in step S406. This processing is the same as the processing in step S115 in FIG. 12, and the description thereof is not repeated.

50 Next, in step S407, the server-controlling CPU 81 clears the number of games and the number of winnings of high-probability bets. Namely, the server-controlling CPU 81 restores both the number of games stored in the number-of-games storage area 200F in the RAM 200 and the number of winnings of high-probability bets stored in the number-of-winnings-of-high-probability-bets storage area 200G to an initial value of 0.

55 After the processing in step S407, the present subroutine ends.

As described above, the roulette gaming machine 1 according to the second embodiment comprises a roulette wheel 22 including a plurality of pockets associated with respective numbers in advance. Further, the roulette gaming machine 1

includes the ROM 102 (memory) which stores a plurality of control data for controlling the roulette gaming machine 1 so as to provide a higher weight on a probability that the ball 27 is housed in any of the number pockets 23 constituting a single area, the single area belonging to the plurality of areas (groups) each of which consists of 6 or 7 pockets of the number pockets 23, and the plurality of control data associated with each of the areas. Furthermore, the roulette gaming machine 1 comprises a plurality of stations 4 for players to play games. Also, the roulette gaming machine 1 comprises a server-controlling portion 80 (controller), and the server-controlling portion 80 controls rotation of the roulette wheel 22 and launching of the ball 27 by referring to a single control data. Further, the server-controlling portion 80 determining a number corresponding to one of the pockets with the ball housed therein as a winning number. Also, the server-controlling portion 80 counts the number of games played. The server-controlling portion 80 also counts the number of winnings of high-probability bets, that is the number of games in which a bet is placed on any of the pockets 23 belonging to the area having the relatively high ball-housing probability at a second predetermined number or more of the stations among a plurality of stations 4, and this bet is determined as a winning bet based on this bet and the determined winning number. Moreover, the server-controlling portion 80 calculates high-probability bet winning frequency, that is frequency of games in which a bet is placed on any of the pockets 23 belonging to the area having the relatively high ball-housing probability at the second predetermined number or more of the stations 4, and this bet is determined as a winning bet based on this bet and the determined winning number. When the above-mentioned high-probability bet winning frequency exceeds a predetermined frequency, the server-controlling portion 80 selects another control data different from the single control data, out of the plurality of control data, to set the selected control data as a reference target.

In the present embodiment, a game in which a high-probability bet is placed at a number of stations 4 equal to or more than the second predetermined number and, further, the high-probability bet is won at a number of stations 4 equal to or more than the third predetermined number is counted as the number of winnings of high-probability bets. However, the present invention is not limited to this example. For example, a game in which a high-probability bet is placed at a number of stations equal to or more than the second predetermined number and the high-probability bet is won at all the stations at which the high-probability bet has been placed may be counted as the number of winnings of high-probability bets.

In the present embodiment, there has been described a case where control data is switched when a high-probability bet is placed at a number of stations equal to or more than the second predetermined number and the high-probability bet is won at a number of stations equal to or more than the second predetermined number. However, in the present invention, control data may be switched when a high-probability bet is placed at a number of stations equal to or more than the second predetermined number and the high-probability bet is won at least a single station or when a high-probability bet is placed at a number of stations equal to or more than the second predetermined number and the high-probability bet is won at all the stations at which the high-probability bet is placed.

In the present embodiment, there has been described a case where the plurality of stations are provided in a roulette gaming machine. However, in the present invention, it is not necessary that the plurality of stations are provided in a roulette gaming machine, but it is only necessary that another

control data different from a single control data is selected out of the plurality of control data, the selected control data is set as a reference target.

Although the present invention has been described with reference to embodiments thereof, these embodiments merely illustrate concrete examples, not restrict the present invention. The concrete structures of respective means and the like can be designed and changed as required. Furthermore, there have been merely described most preferable effects of the present invention, as the effects of the present invention, in the embodiments of the present invention. The effects of the present invention are not limited to those described in the embodiments of the present invention.

Further, in the above-mentioned detailed description, characteristic portions have been mainly described, for ease of understanding the present invention. The present invention is not limited to the embodiments described in the above-mentioned detailed description, but can be also applied to other embodiments over a wider range of applications. Further, the terms and phrases used in the present specification have been used for clearly describing the present invention, not for limiting the interpretation of the present invention. Further, those skilled in the art will easily conceive other structures, systems, methods and the like which are included in the concept of the present invention, from the concept of the present invention described in the present specification. Accordingly, the description of the claims is intended to include equivalent structures that fall within the technical scope of the invention. Further, the abstract aims at enabling engineers and the like who belong to the present technical field but are not familiar with the patent office and public institutions, the patent, law terms and technical terms to immediately understand the technical content and the essence of the present application through brief studies. Accordingly, the abstract is not intended to restrict the scope of the invention which should be evaluated from the description of the claims. It is desirable that literatures and the like which have been already disclosed are sufficiently studied and understood, in order to sufficiently understand the objects of the present invention and the specific effects of the present invention.

In the above-mentioned detailed description, there have been described processes to be executed by computers. The above-mentioned description and expressions have been described for the sake of enabling those skilled in the art to understand the present invention most effectively. In the present specification, each step for deriving a single result should be understood to be self-consistent processing. Further, each step includes transmission, reception, recording and the like of electric or magnetic signals. Although, in the processing at each step, such signals have been expressed as bits, values, symbols, characters, terms, numerical characters and the like, it should be noticed that they have been merely used for convenience of description. Further, although the processing at each step was described using expressions common to human behaviors in some cases, the processes described in the present specification are to be executed by various types of devices, in principle. Further, other structures required for conducting each step will be apparent from the above-mentioned description.

What is claimed as new and desired to be secured by Letters Patent of the United States is:

1. A gaming apparatus comprising:
a roulette wheel including a plurality of pockets associated with respective numbers in advance;
a memory for storing a plurality of control data for controlling the gaming apparatus so as to provide a rela-

tively high weight on a probability that a ball is housed in any of the pockets constituting a single group, said single group belonging to a plurality of groups each of which consists of a first predetermined number of said plurality of pockets, and the plurality of control data associated with each of said groups;

a plurality of stations for players to play games; and

a controller,

said controller programmed to execute the following processes of:

(a) controlling rotation of said roulette wheel and launching of said ball by referring to a single control data out of said plurality of control data, and

(b) selecting another control data different from said single control data, out of said plurality of control data, to set the selected control data as a reference target, when a bet is placed on any of the pockets belonging to a group having said relatively high ball-housing probability at a second predetermined number or more of the stations among said plurality of stations.

2. A gaming apparatus comprising:

a roulette wheel including a plurality of pockets associated with respective numbers in advance;

a memory for storing a plurality of control data for controlling the gaming apparatus so as to provide a relatively high weight on a probability that a ball is housed in any of the pockets constituting a single group, said single group belonging to a plurality of groups each of which consists of a first predetermined number of said plurality of pockets, and the plurality of control data associated with each of said groups;

a plurality of stations for players to play games; and

a controller,

said controller programmed to execute the following processes of:

(a) controlling rotation of said roulette wheel and launching of said ball by referring to a single control data out of said plurality of control data,

(b) counting the number of games played,

(c) counting the number of high-probability bets indicating the number of games in which a bet is placed on any of the pockets belonging to a group having said relatively high ball-housing probability at a second predetermined number or more of the stations among said plurality of stations,

(d) calculating frequency of high-probability bets, that is frequency of games in which a bet is placed on any of the pockets belonging to a group having said relatively high ball-housing probability at said second predetermined number or more of the stations, based on said number of games and said number of high-probability bets, and

(e) selecting another control data different from said single control data, out of said plurality of control data, to set the selected control data as a reference target, when said frequency of high-probability bets exceeds a predetermined frequency.

3. A gaming apparatus comprising:

a roulette wheel including a plurality of pockets associated with respective numbers in advance;

a memory for storing a plurality of control data for controlling the gaming apparatus so as to provide a relatively high weight on a probability that a ball is housed in any of the pockets constituting a single group, said single group belonging to a plurality of groups each of which consists of a first predetermined number of said plurality of pockets, and the plurality of control data associated with each of said groups;

a plurality of stations for players to play games; and a controller,

said controller programmed to execute the following processes of:

(a) controlling rotation of said roulette wheel and launching of said ball by referring to a single control data out of said plurality of control data,

(b) determining a number corresponding to one of said pockets with said ball housed therein as a winning number, and

(c) selecting another control data different from said single control data, out of said plurality of control data, to set the selected control data as a reference target, when a bet is placed on any of the pockets belonging to a group having said relatively high ball-housing probability at a second predetermined number or more of the stations among said plurality of stations, and a prize is determined to be offered based on this bet and the determined winning number.

4. A gaming apparatus comprising:

a roulette wheel including a plurality of pockets associated with respective numbers in advance;

a memory for storing a plurality of control data for controlling the gaming apparatus so as to provide a relatively high weight on a probability that a ball is housed in any of the pockets constituting a single group, said single group belonging to a plurality of groups each of which consists of a first predetermined number of said plurality of pockets, and the plurality of control data associated with each of said groups;

a plurality of stations for players to play games; and

a controller,

said controller programmed to execute the following processes of:

(a) controlling rotation of said roulette wheel and launching of said ball by referring to a single control data out of said plurality of control data,

(b) determining a number corresponding to one of said pockets with said ball housed therein as a winning number,

(c) counting the number of games played,

(d) counting the number of prize offering, that is the number of games in which a bet is placed on any of the pockets belonging to a group having said relatively high ball-housing probability at a second predetermined number or more of the stations among said plurality of stations, and a prize is offered based on this bet and said determined winning number,

(e) calculating frequency of prize offering, that is frequency of games in which a bet is placed on any of the pockets belonging to a group having said relatively high ball-housing probability at said second predetermined number or more of the stations among said plurality of stations, and a prize is offered based on this bet and said determined winning number, and

(f) selecting another control data different from said single control data, out of said plurality of control data, to set the selected control data as a reference target, when said frequency of prize offering exceeds a predetermined frequency.

5. A playing method of a gaming apparatus including a memory and a programmable controller, the method comprising the steps of:

with the programmable controller:

(a) controlling rotation of a roulette wheel and launching of a ball by referring to a single control data, the single control data selected out of a plurality of control data

stored in the memory for controlling the gaming apparatus so as to provide a relatively high weight on a probability that said ball is housed in any of the pockets constituting a single group, said single group belonging to a plurality of groups each of which consists of a first predetermined number of pockets out of a plurality of pockets being included in said roulette wheel and being associated with respective numbers in advance; and

(b) selecting another control data different from said single control data, out of said plurality of control data stored in the memory, to set the selected control data as a reference target, when a bet is placed on any of the pockets belonging to a group having said relatively high ball-housing probability at a second predetermined number or more of the stations among a plurality of stations for players to play games.

6. A playing method of a gaming apparatus including a memory and a programmable controller, the method comprising the steps of:

with the programmable controller:

(a) controlling rotation of a roulette wheel and launching of a ball by referring to a single control data, the single control data selected out of a plurality of control data stored in the memory for controlling the gaming apparatus so as to provide a relatively high weight on a probability that said ball is housed in any of the pockets constituting a single group, said single group belonging to a plurality of groups each of which consists of a first predetermined number of pockets out of a plurality of pockets being included in said roulette wheel and being associated with respective numbers in advance,

(b) counting the number of games played,

(c) counting the number of high-probability bets, that is the number of games in which a bet is placed on any of the pockets belonging to a group having said relatively high ball-housing probability at a second predetermined number or more of the stations among a plurality of stations for players to play games,

(d) calculating frequency of high-probability bets, that is frequency of games in which a bet is placed on any of the pockets belonging to a group having said relatively high ball-housing probability at said second predetermined number or more of the stations, based on said number of games and said number of high-probability bets, and

(e) selecting another control data different from said single control data, out of said plurality of control data stored in the memory, to set the selected control data as a reference target, when said frequency of high-probability bets exceeds a predetermined frequency.

7. A playing method of a gaming apparatus including a memory and a programmable controller, the method comprising the steps of:

with the programmable controller:

(a) controlling rotation of a roulette wheel and launching of a ball by referring to a single control data, the single control data selected out of a plurality of control data stored in the memory for controlling the gaming apparatus so as to provide a relatively high weight on a

probability that said ball is housed in any of the pockets constituting a single group, said single group belonging to a plurality of groups each of which consists of a first predetermined number of pockets out of a plurality of pockets being included in said roulette wheel and being associated with respective numbers in advance,

(b) determining a number corresponding to one of said pockets with said ball housed therein as a winning number, and

(c) selecting another control data different from said single control data, out of said plurality of control data stored in the memory, and setting the selected control data as a reference target, when a bet is placed on any of the pockets belonging to a group having said relatively high ball-housing probability at a second predetermined number or more of the stations among a plurality of stations for players to play games, and a prize is determined to be offered based on this bet and said determined winning number.

8. A playing method of a gaming apparatus including a memory and a programmable controller, the method comprising the steps of:

with the controller:

(a) controlling rotation of a roulette wheel and launching of a ball by referring to a single control data, the single control data selected out of a plurality of control data stored in the memory for controlling the gaming apparatus so as to provide a relatively high weight on a probability that said ball is housed in any of pockets constituting a single group, said single group belonging to a plurality of groups each of which consists of a first predetermined number of pockets out of a plurality of pockets being included in said roulette wheel and being associated with respective numbers in advance,

(b) determining a number corresponding to one of said pockets with said ball housed therein as a winning number,

(c) counting the number of games played,

(d) counting the number of prize offering, that is the number of games in which a bet is placed on any of the pockets belonging to a group having said relatively high ball-housing probability at a second predetermined number or more of the stations among a plurality of stations for players to play games, and a prize is offered based on this bet and said determined winning number,

(e) calculating frequency of prize offering, that is frequency of games in which a bet is placed on any of the pockets belonging to a group having said relatively high ball-housing probability at said second predetermined number or more of the stations, and a prize is offered based on this bet and said determined winning number, and

(f) selecting another control data different from said single control data, out of said plurality of control data stored in the memory, to set the selected control data as a reference target, when said frequency of prize offering exceeds a predetermined frequency.
